(57) **CLAIM**

The ornamental design for an apparatus for incapacitating an active shooter, as shown and described.

DESCRIPTION

FIG. 1 is a front perspective view of an apparatus for incapacitating an active shooter, in a storage configuration, according to the present invention.

FIG. 2 is a front view thereof.

FIG. 3 is a rear view thereof.

FIG. 4 is a left view thereof.

FIG. 5 is a right view thereof.

FIG. 6 is a top view thereof.

FIG. 7 is a bottom view thereof.

FIG. 8 is a top front perspective view thereof, shown in a deployed configuration.

FIG. 9 is a top and rear perspective view thereof;

FIG. 10 is a front view thereof.

FIG. 11 is a rear view thereof.

FIG. 12 is a left view thereof.

FIG. 13 is a right view thereof.

FIG. 14 is a top view thereof; and,

FIG. 15 is a bottom view thereof.

1 Claim, 13 Drawing Sheets
